UNITED STATES PATENT OFFICE.

ARVID M. ANDERSON AND WALTER W. ABITZ, OF ROCKFORD, ILLINOIS.

DESIGN FOR A CAN-OPENER.

54,364.

Specification for Design.

Patented Feb. 10, 1920.

Application filed August 25, 1919. Serial No. 319,831. Term of patent 7 years.

To all whom it may concern:

Be it known that we, ARVID M. ANDERSON and WALTER W. ABITZ, citizens of the United States, residing at Rockford, in the county of Winnebago and State of Illinois, have invented a new, original, and ornamental Design for a Can-Opener, of which the following is a specification, reference being had to the accompanying drawing, forming part thereof:

In the drawing,—

Figure 1 is a side elevation of a can opener showing our new design;

Figs. 2 and 3, plan and end views, respectively, thereof; and

Fig. 4, a sectional view taken on the line 4—4 of Fig. 1.

We claim:—

The ornamental design for a can opener, as shown.

ARVID M. ANDERSON.
WALTER W. ABITZ.
